WATER VALVE

George H. Fuehrer, Easton, Pa., assignor to Ingersoll-Rand Company, Jersey City, N. J., a corporation of New Jersey

Application April 28, 1922. Serial No. 607,980

1 Claim. (Cl. 251—44)

This invention relates to valves, and more particularly to water valves for rock drills equipped with means for flushing the cuttings from the drill hole.

5 One object of the invention is to assure the introduction of cleansing water to the drill hole throughout the entire operative period of the rock drill.

Other objects will be in part obvious and in 10 part pointed out hereinafter.

In the accompanying drawing forming a part of this specification and in which similar reference characters refer to similar parts,

Figure 1 is a sectional elevation of a rock drill 15 to which the invention is applied, and

Figure 2 is a transverse view taken through Figure 1 on the line 2—2 looking in the direction indicated by the arrows.

Referring more particularly to the drawing, 20 the rock drill A comprises a cylinder B, only a portion of which is shown, and a back head C which acts as a closure for the rear end of the cylinder B and to which it may be secured by side bolts D arranged on opposite sides of the rock drill.

Within the cylinder B is a piston chamber E to accommodate a reciprocating hammer piston F whereby the working implement (not shown) is actuated.

25 In the rear end of the cylinder B is an enlarged bore G to accommodate rotation mechanism H, of a well known type adapted to effect rotary movement of the working implement, and valve mechanism J for distributing pressure fluid to the ends of the piston chamber E to actuate the piston F.

The back head C also serves as a casing for a 30 throttle valve K which controls the admission of pressure fluid to the valve mechanism J. The throttle valve K may, as illustrated, be in the form of a cylindrical plug having a recess L into which pressure fluid may be constantly introduced by a connection O leading from a source of supply, and on an end of the throttle valve is a lever P whereby it may be manipulated. In the wall 35 of the throttle valve and leading from the recess L is a laterally extending port or passage Q which, in the open position of the throttle valve, registers with a supply passage R extending through the back head C and the rotation mechanism H to the valve mechanism J.

In accordance with a well known practice, the 40 rock drill A is provided with a tube S for conveying water into the working implement through 45 which the water passes to flush the cuttings from

the drill hole. The tube S extends through the rotation and valve mechanisms and through the cylinder and carries at its rear end a flange T which lies in a recess U in the back head C. The outer portion of the recess U is suitably threaded to accommodate a plug V which seats 60 against the flange L for clamping the tube S fixedly in position. In the end of the plug V adjacent the flange T is a passage W having a branch X to afford communication between the recess U and the bore in the tube S.

65 The water which the tube S is intended to convey to the working implement is supplied to the rock drill by a connection Y threaded into the end of a passage Z in the back head C. In accordance with the present invention, the passage Z opens into a bore b which is located in the back head C and extends laterally of the throttle valve K. Into the outer end of the bore b is threaded a plug c having a passage d to convey the water to a passage e leading from the bore b to the recess U.

70 Disposed in the inner end of the bore b is a guide bushing f having a bore g to slidably receive a plunger h which extends with one end into the chamber j wherein the throttle valve K is arranged, and on the throttle valve K is a cam surface k to act against the adjacent end of the plunger h for actuating the plunger in the direction of the plug c.

75 Near the opposite end of the plunger h is an 80 external bevelled shoulder o adapted to seat against a seating surface p on the guide member f to effect a seal at this point for preventing leakage of water through the bore g into the 85 throttle valve chamber j. The plunger h is, moreover, provided with a recess q for the accommodation of a needle valve r arranged coaxially with the outlet end of the passage d and wherewith it cooperates to control the flow of 90 water from the passage d to the passage e.

95 In order to prevent injury to the needle valve r, such as might be caused by pressing the needle valve forcibly against the plug c a spring s is 100 disposed in the recess q to transmit the movement of the plunger h to the needle valve. The needle valve r may be held against displacement from the recess q in any suitable manner, as for instance by forming a head t on that portion of the valve which lies within the recess q and peening or rolling the end of the plunger h to form a shoulder u against which the head t may seat.

To the end that the needle valve r may be 105 promptly opened when the throttle valve K is being rotated to move the cam surface k out of 110

engagement from the plunger *h* a spring *v* is disposed in the bore *g* to seat with one end against the plug *c* and with its other end against the shoulder *o*.

- 5 The operation of the device briefly described is as follows: By rotating the throttle valve *K* to the open position the cam surface *k* will be moved out of contact from the plunger *h*. The spring *v* will then actuate the plunger to press 10 the shoulder *o* against the seating surface *p*, thus preventing leakage of water from the bore *b* through the bore *g* into the throttle valve chamber *j*. Being interlocked with the plunger *h* the needle valve *r* will be moved therewith to the 15 open position to permit the flow of water from supply through the bore *b* and the associated passages into the tube *S* and the needle valve *r* will be held open by the spring *v* as long as the throttle valve *K* remains in the open position.
- 20 Upon rotation of the throttle valve *K* to its closed position the cam surface *k* acts against the end of the plunger *h* and will actuate the plunger, together with the valve *r*, in the direction of the passage *d*, the outlet end of which 25 it controls. In this way the needle valve *r* will

be promptly closed to cut off the supply of water to the tube *S* before the supply of pressure fluid to the rock drill has been completely cut off by the throttle valve *K*. During the subsequent closing movement of the throttle valve *K* the plunger *h* compresses the spring *s* and causes it to exert a sufficiently heavy pressure against the needle valve *r* to assure against leakage of water from the passage *d* into the bore *b* during the inoperative periods of the rock drill.

I claim:

Valve mechanism comprising a casing having a bore and inlet and outlet passages opening into the bore, a plunger slidable in the bore and having a recess, a spring-pressed needle valve slidable in the recess and cooperating with the outlet end of the inlet passage to control communication between the inlet passage and the bore, bevelled sealing surfaces on the plunger and the casing, and a spring in the bore acting against the plunger to open the valve and to maintain the sealing surfaces in sealing relationship with each other during the time the valve occupies its open position.
